CLAIM

The ornamental design for a pet animal litter box as shown and described.

DESCRIPTION

FIG. 1 is a perspective view of the pet animal litter box showing upper, front, and right sides of said box.

FIG. 2 is an alternative perspective view of the pet animal litter box showing upper, rear, and left sides of said box; and, FIG. 3 is a bottom view of the pet animal litter box. Dashed or broken lines appearing in the drawings represent die cut slits and form part of the design.
